UNITED STATES PATENT OFFICE.

OSCAR H. PIEPER AND ALPHONSE F. PIEPER, OF ROCHESTER, NEW YORK.

ELECTROLYTIC CELL.

1,024,597.

Specification of Letters Patent. Patented Apr. 30, 1912.

Application filed October 9, 1908. Serial No. 456,922.

To all whom it may concern:

Be it known that we, OSCAR H. PIEPER and ALPHONSE F. PIEPER, of Rochester, in the county of Monroe and State of New York, have invented certain new and useful Improvements in Electrolytic Cells; and we do hereby declare the following to be a full, clear, and exact description of the same, reference being had to the accompanying drawings, forming a part of this specification, and to the reference-numerals marked thereon.

The present invention relates to electrolytic cells particularly of the type employed as alternating current rectifiers which embody an electrolytic-containing receptacle forming an inert electrode and an active electrode arranged in the receptacle, and it has for an object to provide an improved construction which shall have a maximum radiating surface to dissipate the heat generated in the cell.

Another object is to collect the precipitated matter in such a manner that it will not interfere with the circulation of the electrolyte, nor act to short circuit the cell by connecting the two electrodes.

To these and other ends the invention consists in certain improvements and combinations of parts all as will be hereinafter more fully described, the novel features being pointed out in the claim at the end of the specification.

In the drawings: Figure 1 is a plan view of the receptacle electrode; Fig. 2 is an end view; Fig. 3 is a vertical longitudinal section; and Fig. 4 is a detail horizontal section.

The present embodiment of the invention employs an electrode chamber 1 open at its top 2 and having hollow ribs 3 each extending on opposite vertical walls and around the bottom to receive the electrolyte and quickly dissipate the heat contained therein.

In order to further increase the radiation of the cell, there are provided hollow radiating chambers 4 preferably arranged in two series, the members of which are connected by passageways 5 at their tops and bottoms. One member of each series is connected to the top and the bottom of the elec-

trode chamber 1 by passages 6 and 7 on those sides of said chamber at right angles to the ribbed sides. These radiating chambers are formed of two vertical legs connected at their tops and bottoms, and with these top and bottom portions the passageways 5, 6 and 7 connect. The height of each radiating chamber is materially less than that of the electrode chamber so that the latter projects above and below the radiating members. The projection of the electrolyte chamber above the radiating chambers permits the radiating chambers to be filled to their top with the electrolyte, thus providing a perfect circulation, and the connections or passageways 6 and 7 by leading from upper and lower portions that connect the legs of the units 4 prevent any dead spaces being formed above or below the connections. The ends of chambers 4 have openings alined with passages 5, 6 and 7 and closed by screw plugs 8 to permit the cleaning of the chambers.

Arranged in the electrode chamber is the active electrode 9 which in this instance is in the form of a stick of aluminum. It may be supported by a perforated and removable closure 10 for the electrolyte chamber and carry a binding post 11 by which a conductor is secured, the other binding post 12 being carried by a plug 8 in order to be electrically connected to the hollow electrode 1. The electrode 9 has its lower end arranged above the bottom of the passageways 7 and as the electrolyte chamber 1 depends below these passageways a compartment is provided to hold the precipitate so that the latter cannot interfere with the circulation or cause a short circuit between the electrodes 1 and 9.

An electrolytic cell constructed in accordance with this invention is inexpensive to manufacture and may be cast in one piece so that it is not liable to leak. Further the parts are so formed that a maximum radiating surface is obtained without unduly increasing the size of the cell.

We claim as our invention:

An electrolytic cell comprising a hollow electrode chamber and radiating chambers with passageways connecting them at the

tops and bottoms and also connecting them with electrode chamber, the bottom of the latter being lower than the bottom of the other chambers and forming a sediment collecting pocket, said chambers and passageways being formed in an integral casting having apertures in alinement with the pas-

sageways and clean out plugs fitted in said apertures.
